210,007

BUILDING

Victor J. Cassano, 3270 Governor Trail,
Dayton, Ohio 45409

Filed July 31, 1967, Ser. No. 8,070

Term of patent 7 years

(Cl. D13—1)

Fig. 1

Fig. 2

Fig. 3

What is claimed is:

The ornamental design for a building, substantially as shown and described.
